DESIGN.

L. H. MARSTON.

ORGAN CASE TOP.

No. 19,068.

Patented Apr. 30, 1889.

UNITED STATES PATENT OFFICE.

LOUIS H. MARSTON, OF CHICAGO, ILLINOIS.

DESIGN FOR AN ORGAN-CASE TOP.

SPECIFICATION forming part of Design No. 19,068, dated April 30, 1889.

Application filed March 1, 1889. Serial No. 301,705. Term of patent 3½ years.

To all whom it may concern:

Be it known that I, LOUIS H. MARSTON, a citizen of the United States, residing at Chicago, county of Cook, and State of Illinois,

- have invented and produced a certain new and original Design for an Organ-Case Top, set forth in the following specification, reference being had to the accompanying engraving, forming a part thereof.
- 10 This design comprises two subordinate designs, one for an organ-case ornamental top and the other for an organ-case desk-top, each of which is capable of being produced independently and separately, but which, when 15 combined, constitute a unitary design for an organ-case top.

Referring to the illustration of the design herewith, the organ-case ornamental top comprises that portion of the entire top located 20 above the plane of the entablatures B B, and the organ-case desk-top comprises that portion which is included between the organ-case entablature A and the ornamental top as above defined.

25 The characteristic features of this design, considered as a whole, are found in the alcoves C C, one at each end, and in the alcoves E E, directly above the alcoves C C, the mirror-backed alcove F above the desk, and the upper corner pockets or open-topped alcoves, G G; and the design is characterized by the following special peculiarities of said parts, respectively: At each end of the music-desk there is located an alcove, C, which has the 30 outer forward corner C', defining the alcove at that limit, and is surmounted by the entablature B, slightly projecting. The open front is relieved from the appearance of blankness by the depending bracket C'', and the alcove is 35 lightened by the opening C''' through the outer end, admitting light thereinto, and, further, by the mirror C'', with which it is backed. The ornamental top above the entablatures B comprises two open-front and open-end alcoves, 40 E E, located directly above the alcoves C C, respectively, the entablatures B constituting their lower limit, each of said entablatures having the outer forward ornamental corner E', and each being surmounted by an entablature, 45 H, slightly projecting at the front and side. Both front and side openings of these alcoves

are relieved by depending ornamental brackets E² and E³, respectively, and each alcove has an opening, E⁴, into the mirror-backed central alcove, F. The back of this organ-top as an entirety is of full width to the top, presenting either to direct front or direct rear view a rectangular appearance. Directly above the alcoves E E, and having as their lower limits the entablatures H, are the upper corner pockets, G G, which are defined by the back G' and the forward fence, G², and the outer fence, G³. The back G' constitutes the upper corner of the entire organ-back. The forward and outer fences, G² and G³, slope downward each toward 65 the lower forward corner, G⁴, at which they unite, the two fences having substantially the same slope, but in planes at right angles to each other, as illustrated. The effect of this feature in the design is to relieve the boldness of the upper outline of the entire organ-top, which is caused by the rectangular back, because in any other than direct front view the upper outline will at one corner or the other include the sloping upper edge of the fence 70 G³ of the pocket G, so that by combining this sloping fence with the square back there are obtained both the vigorous effect of the square outline, which is always seen at one corner, and the sloping outline, which will be seen at 75 the other corner.

I claim—

1. The design for an organ-top herein shown and described, having a rectangular back of full width to the top, comprising open-fronted 85 alcoves, one at each end of the music-desk, having ornamental outer forward corners surmounted by plain entablatures, and having the front openings relieved by brackets depending from said entablatures, respectively, 90 a central mirror-backed alcove above the music-desk, and at each end thereof an alcove open at front and outer ends and having an ornamental outer front corner and surmounted by a plain entablature, and having the 95 openings relieved by brackets depending from said entablature, and the upper corner pockets, G, having the outer fence sloping from the extreme upper corner of the back down and forward to a low outer forward corner of the 100 pocket, substantially as set forth.

2. In a design for an organ-top, the design

for an ornamental top herein shown and described, which comprises a rectangular back of full width to the top, and upper forward corner pockets, G, having their outer side 5 fences sloping down forwardly from the extreme outer corner of the back to the low outer forward corner of the pocket, substantially as set forth.

3. In a design for an organ-top, the design 10 for the music-desk top herein shown and described, comprising the music-desk and an open-fronted alcove at each end thereof, having an ornamental outer front corner and sur-

mounted by a plain entablature, and having its front opening relieved by a bracket 15 pending from such entablature, substantially as set forth.

In testimony whereof I have hereunto set my hand, in the presence of two witnesses, at Chicago, Illinois, this 25th day of February, 20 1889.

LOUIS H. MARSTON.
